UNITED STATES PATENT OFFICE.

JOHN FAULDS, OF OAK PARK, ILLINOIS, ASSIGNOR OF ONE-HALF TO JOHN I. MARSHALL, OF CHICAGO, ILLINOIS.

BAKE-OVEN.

1,078,667.

Specification of Letters Patent. Patented Nov. 18, 1913.

Application filed March 8, 1912. Serial No. 682,460.

To all whom it may concern:

Be it known that I, JOHN FAULDS, a subject of the Kingdom of Great Britain, and a resident of Oak Park, county of Cook, and 5 State of Illinois, have invented certain new and useful Improvements in Bake-Ovens, of which the following is a specification, and which are illustrated in the accompanying drawings, forming a part thereof.

10 The invention relates to bake ovens and particularly to those adapted for continuous baking through being heated by radiation from the walls of a furnace, and from the walls of flues within which the furnace gases 15 are confined.

One of the objects of the invention is to provide for a more efficient distribution of the heat in bake ovens of the kind described, and a feature of the invention provides for 20 more intensely heating that part of a baking compartment adjacent its doors in order that the loaves which are inserted last, during the filling of the compartment, may nevertheless be colored first to permit their 25 removal to provide access to the loaves more remote from the doors.

In the accompanying drawings: Figure 1 is a perspective view of a bake oven embodying the features of improvement provided 30 by the invention, some of the parts being broken away to show the internal construction of the oven; Fig. 2 is a plan view of the same, some of the parts being broken away; Fig. 3 is a detail rear elevation of the oven, 35 the rear end wall being removed; Fig. 4 is a central vertical longitudinal sectional view of the oven; Fig. 5 is a detail sectional view taken on the line 5—5 of Fig. 4; Fig. 6 is a detail sectional view taken on the line 40 6—6 of Fig. 2; and Fig. 7 is a detail central transverse sectional view showing a modified form of construction.

As shown in the drawings, the oven is of a form having sectional walls whereby it 45 may be reduced to compact form for transportation from place to place, and may be erected for use upon the ground over a trench adapted to receive the fire. Preferably the oven structure is of oblong rectangular shape, the length of the structure from side to side of the oven being considerably greater than that measured from the front to the back of the oven. The front and rear walls of the oven are designated 10 and 11,

respectively. The side walls are designated 55 12 and 13. Each of the walls 10, 11, 12 and 13 takes the form of a continuous slab, preferably having inner and outer surface plates 14, 15, of sheet metal, and an intermediate filling 16 of non-conducting material, such 60 as mineral wool. In order that the side and end walls may be detachably connected they are preferably provided, respectively, with registering dowel pins 17 and apertures 18. As shown the dowel pins 17 are located upon 65 the ends of the side walls 12 and 13, and the apertures 18 are located in the front and rear walls 10 and 11 adjacent their vertical edges. Preferably the dowel pins 17 are of sufficient length to project through the aper- 70 tures far enough to receive cotter pins 19. The cotter pins 19 are most conveniently permanently connected to the front and rear walls 10 and 11 adjacent the several apertures 18 by chains 20, to prevent their being 75 misplaced.

A chambered cover 21 is provided for the structure. As shown this cover has marginal flanges 22, adapted to rest upon the upper edges of the side and end walls 10, 11, 80 12 and 13. An upstanding flange 23 extends along the higher edge of each of the side and end walls 10, 11, 12 and 13, whereby, when the parts are fitted together, a continuous ledge is formed about the margins of the 85 cover 21 for confining a layer 24 of sand or other heat-retaining material upon the top of the cover.

Preferably the space inclosed by the cover 21 and vertical walls 10, 11, 12 and 13, is 90 horizontally divided by means of a partition or shelf 25, which constitutes a hearth for receiving the loaves to be baked. As shown the shelf 25 has upper and lower surface plates 26, 27, of sheet metal, and an intermediate filling 28 of mineral wool or other insulating material. For removably supporting the shelf in position the front and rear walls 10, 11, are provided with horizontal ledges 29 upon their inner faces at about 100 midway of their height. The ledges 29 may be conveniently formed by securing Z-bars to the inner surface plates 15 of the front and rear walls 10 and 11. When the ledges 29 are formed in this way the shelf 25 is 105 preferably provided with downturned flanges 69 at its opposite edges. These downturned flanges hook over the upstand-

ing edges of the Z-bars whereby the shelf 25 serves to connect the opposite side walls of the casing and prevents their bulging.

Access to the baking compartment is preferably had through downwardly-opening doors 30 and 31 provided in the front wall 10 above the shelf 25. Preferably each of these doors is nearly equal in width to half the length of the front wall 10, and each is hinged at its lower edge to the outer surface plate 14 of the front wall 10 adjacent the corresponding door opening, as shown at 32, Fig. 4. In order that the door when open may serve as a peel rest, the movable plates 15 of the hinges 32 carry stop lugs 33 adapted to engage the front wall 10 to support the door in a horizontal position. Swinging latch arms 34 are applied to each of the doors 30 and 31, and coöperating cleats 35 20 are applied to the outer face of the front wall 10 above the door openings. As shown, two latch arms 34 are mounted upon each of the doors 30 and 31. The latch arms 34 on each door are connected to move together by 25 a strap 36, carrying a hand-piece or grip 37.

When the walls 10, 11, 12 and 13, and the cover 21 are detachably connected, as shown, the structure is preferably formed without a bottom or floor other than the ground X 30 on which it rests. In erecting the oven for use it is preferably located over a trench Y, for receiving a fire. Most desirably the trench Y is of sufficient length to extend rearwardly from the front wall 10 to beyond the rear wall 11, in order that access to the trench for tending the fire may be had from in rear of the oven. For protecting the under side of the shelf 25 from the direct heat of the fire contained in the 35 trench Y, and to permit of the flue gases from the fire being confined in passages leading through the baking compartment and discharging into the chamber of the roof or cover 21, a bottomless box 38 is placed over the trench within the structure. This box is preferably substantially equal in 40 length to the distance between the front and rear walls 10 and 11. As shown, it has side and end flanges 39, 40, upon its lower edges. The side flanges 39 provide a substantial 45 support for the box upon the ground X adjacent the trench Y. The possibility of caving in of the walls of the trench is thus reduced. For receiving the end flanges 40 of the box 38, inturned flanges 41 are provided upon the lower edges of the front and rear walls 10 and 11. The flanges 40 and 41 have coöperating dowel pins 42 and apertures 62 for preventing accidental displacement 50 of the box 38 in use. For controlling the fire within the trench Y a swinging door 43 is hung from the lower edge of the rear wall 11 to enter the trench. As shown, brackets 44, carrying hinged pintles 45, are 55 secured to the lower edge of the rear wall 11

over the trench Y and the door 43 carries hinge plates 46 having slotted openings 47 for receiving the pintles 45. By reason of the sliding engagement between the door 43 and brackets 44 thus provided, the door may 60 be moved inwardly when raised, to cause its inner edge to pass under the lower edge of the rear wall 11, whereby the door is supported in a horizontal position. When it is desired to reduce the supply of air to the 65 fire in the trench Y, the door 43 may be pulled forwardly to release its inner edge from the under side of the wall 11 when it may be permitted to fall to a transverse vertical position within the trench. 70

Flues 48, 49, lead from the box 38 to the chamber of the roof or cover 21, and a stack 50 leads out of the chamber of the cover. Preferably provision is made for so conducting the flue gases from the fire in the trench 75 Y that the baking chamber will be more intensely heated adjacent the front wall 10. As shown, the flues 48, 49, lead from opposite sides of the box 38 adjacent its front end, first horizontally to the sides of the 80 structure, and then upwardly to the chamber of the roof 21. The stack 50 is preferably located upon the median line of the structure adjacent the rear wall 11, and partitions are provided within the chamber of 85 the roof 21 to confine the flue gases to a definite path in passing from the flues 48, 49, to the stack.

As most clearly shown in Fig. 2 of the drawings, partitions 51, 52, extend within 90 the chamber of the cover 21 from the sides of the chamber in rear of the flues 48, 49, toward but short of the median line of the chamber, thus providing a port opening 54 between their ends. A partition 53, parallel 95 with the partitions 51, 52, extends across the median line of the roof chamber in front of the stack 50 and provides port openings 63, 64, beyond its ends. By means of the arrangement of flues 48, 49, and partitions 51, 52, 100 53, the flue gases from the fire are led laterally in opposite direction to the sides of the oven, then upwardly through the baking compartment adjacent the front wall 10, and on being discharged into the chamber of the 105 cover 21 are required to pass over the baking compartment adjacent the front wall to the port opening 54. To reach the stack 50, the flue gases must then pass about the ends of the partition 53, whereby an efficient distribution of heat over the baking compartment is provided. The shelf 25 is also heated throughout its entire extent from below by direct radiation of heat from the 110 walls of the box 38, and by contact with the heated air confined within the structure below the shelf. 115

Preferably the flues 48, 49, and the stack 50 are detachably secured in place. As shown, the horizontal and vertical portions 120

130

of the flues 48, 49, are formed in separable sections adapted for telescopic connection in the usual way of connecting smoke flues, as shown at 55, Fig. 5. For convenience in assembling the parts the horizontal portions of the flues 48 and 49 extend in alinement over the fire box cover 38 and the latter is provided with a flanged opening 56 which enters such flue passage. A flange or collar 58 is provided upon the upper wall of the cover 21 for telescopically receiving the lower end of the stack 50. As shown, this flange or collar 58 has a sliding connection with the upper wall of the cover 21 in order that it may be substantially concealed within the chamber of the cover when not in use. For supporting the collar 58 in its elevated position of service, oppositely fastening cleats 59, 60, are secured to the under side 20 of the upper wall of the cover adjacent the stack opening, and a bar 61 extends diametrically through the collar and has its ends projecting beyond the collar to engage the cleats. When it is desired to lower the collar to a position in which it is substantially concealed within the chamber of the cover 21, the stack 50 being removed, an intermediate portion of the bar 61 may be grasped by the hand and the collar 58 thereby given a partial rotation to disengage the ends of the bar 61 from the cleats 59, 60. Similarly, the bar 61 may be grasped by the hand for raising the collar 58, and when the collar has been thus raised it may be given a 35 partial rotation to bring the ends of the bar 61 into engagement with the cleats 59, 60. The large doors 30 and 31 provide convenient access to the whole of the baking chamber. The flues 48, 49, and partitions 40 51, 52, confine the hottest gases from the fire to the front portion of the oven structure in order that the baking may proceed somewhat more rapidly adjacent the doors than at the rear portions of the baking compartment. Opportunity for filling the compartment adjacent the doors after the rear portions of the compartment have been filled, and for removing the contents of the compartment about the doors to provide access 45 to the material contained in the rear portions of the compartment, is thus provided. The structure described may be erected for use at any place upon the ground where a trench Y may be formed, and it may be 50 conveniently taken down for transportation from place to place. An efficient baking oven, suitable for use as a part of the camp equipment of armies in the field, or of large camping parties, is thus provided.

60 In some instances it may be desirable to form the cover 21 in two parts, as 65, 66, adapted to be joined together upon the median line of the oven, as at 67, Fig. 7. The collar 58 for receiving the stack is then preferably located a short distance at one side

of the median line of the oven, in order that it may be carried wholly by one of the parts, as 66, of the cover. To make a tight joint between the parts 65, 66, of the cover, a flange 68, adapted to telescopically enter the open end of one of the parts, as 65, is formed upon the meeting edge of the other part, as 66.

I claim as my invention:

1. In a bake oven in combination, a bottomless rectangular casing, the walls and roof of the casing being each formed from a single rigid slab and the roof slab being chambered, a shelf detachably supported upon the said wall slabs and dividing the chamber of the casing into upper and lower compartments and constituting a hearth, a cover for a fire box chamber located below the said hearth and a flue pipe detachably connected at its opposite ends to the said cover and roof slab respectively and leading from the said fire box chamber, through an opening in the said hearth to the chamber of the roof slab.

2. In combination, a bake chamber having a charging door at one side, a fire box and means for concentrating the heat from the fire box about that part of the bake chamber adjacent the said charging door comprising a smoke flue leading from the said fire box entirely about the bake chamber adjacent the side having the charging door and along that part of the bake chamber remote from the charging door at the top only.

3. In a bake oven in combination, a bottomless casing having vertical side walls and a roof, a ledge having an upstanding flange at its outer edge extending horizontally across the inside face of each of two opposite side walls, a hearth supported by the said ledges, the corresponding edges of the hearth being provided with down-turned flanges which are hooked over the upturned flanges of the ledges whereby the hearth prevents bulging of the said vertical walls of the casing and a fire box located below the hearth.

4. In combination, a bake chamber having a charging door at one side, a fire box and means for concentrating the heat from the fire about that part of the bake chamber adjacent the said charging door comprising a smoke flue leading from the fire box entirely about the bake chamber adjacent the side having the charging door the said smoke flue being of less width than the width of the bake chamber.

5. In a bake oven, in combination, a rectangular casing, a shelf dividing the chamber of the casing into upper and lower compartments, a charging door in one side of the casing above the shelf, a fire-box located below the shelf, and means for concentrating the heat from the fire-box about that part of the upper compartment adjacent the

said charging door comprising a pair of flues of less width than the width of the casing leading from the fire-box upwardly at opposite ends of the casing adjacent that side of the same having the charging door and thence in opposite directions across the top of the said upper compartment adjacent the same side of the casing to a juncture.

6. In a bake oven, in combination, a rectangular casing, a shelf dividing the chamber of the casing into upper and lower compartments, a charging door in one side of the casing above the said shelf, a fire-box located at the mid-length of the casing and extending substantially from side to side of

the same below the said shelf, and means for concentrating the heat from the fire-box about that part of the said upper compartment adjacent the said charging door comprising a pair of smoke flues of less width than the width of the casing leading in opposite directions from the fire-box adjacent that side of the casing having the charging door, thence upwardly at the ends of the casing to a juncture at the top of said upper compartment.

JOHN FAULDS.
